UNITED STATES PATENT OFFICE.

WILLIAM T. STEIGER AND WALTER H. STEIGER, OF HOWARD COUNTY, MARYLAND, ASSIGNORS OF ONE-THIRD TO ANDREW W. STEIGER, OF NEW YORK, N. Y.

DEVICE FOR PREVENTING SNOW-DRIFTS IN ROAD-CUTS, &c.

SPECIFICATION forming part of Letters Patent No. 319,143, dated June 2, 1885.

Application filed March 23, 1885. (No model.)

To all whom it may concern:

Be it known that we, WILLIAM TELL STEIGER and WALTER HENRY STEIGER, citizens of the United States, and residing in the county 5 of Howard and State of Maryland, have invented certain new and useful Devices for Preventing Snow Drifts or Blockades in Road-Cuts and other Places, of which the following is a specification.

10 Our invention relates to certain devices adapted to prevent the formation of snow drifts or blockades in railroad-cuts or other places liable to a like obstruction; and its operation is based upon the following well-known 15 fact, to wit: When the wind blowing across a stretch of country meets an obstruction or passes over a depression in the surface of the ground, a partial vacuum is formed on the lee side of such obstruction, or within the depression or cut near the windward side thereof, and any particles of ice or snow which may be carried by the wind over or into said vacuum will, by having their relative weight increased, be precipitated to the ground, and any accumulation 20 of such particles will form a drift, or, as applied to roads, a blockade. This action is more noticeable in railway-cuts, more especially so when the wind is blowing at right angles, or nearly so, to the axis thereof. By 25 careful observation it has been ascertained that by preventing the formation of the partial vacuum above mentioned the floating particles of ice and snow are sustained in the air and carried by the wind over and beyond the point where the drift would have formed 30 had the vacuum been allowed to form. We propose, by a simple arrangement of deflecting fences or walls, to deflect a portion of the wind blowing over the cut or obstruction, and 35 cause it to supply a counter or cross current within said cut or behind such obstruction, to prevent the formation of a vacuum.

40 In the accompanying drawings, Figure 1 is a transverse section of a railroad-cut, illustrating the formation of a snow-drift. Fig. 2 is a plan of such a cut and a diagram view of deflecting fences or walls, whereby we propose to prevent the formation of such drifts.

In Fig. 1, *a* represents the general surface-

line of the ground; *b*, the railroad-cut, and 50 the arrow *d* the direction of the wind. Immediately behind the bank of the cut toward the wind, as at *c*, a partial vacuum is formed, and the particles of ice and snow carried along by the wind in the direction of the wind, as 55 shown by the small arrows, will, when they arrive at a point over the vacuum *c*, have their relative weight increased, and be precipitated into said vacuum, and fall to the ground, an accumulation of such particles forming a drift, 60 as at *e*.

In Fig. 2, *a* is the surface of the ground, and *b* the axial line of the cut. At either or both ends of the cut two sets of deflecting fences or walls, *f f' f''*, are erected, and the several 65 fences or walls in each set are made to converge to a point conveniently near the mouth of the cut, and the fences or walls of each set are preferably made to form an angle of forty-five degrees each with the other, the central 70 one being set at an angle of ninety degrees with the axis of the cut. This arrangement seems to be the most effective; but we do not wish to confine ourselves strictly thereto, as in certain locations, owing to the peculiar 75 formation of the ground, other positions for the deflecting fences or walls may be found more effective, as well as an increased or diminished number. We may also place in the cut one or more deflecting guide-fences in front 80 of the air-currents, so as to divert them from the lee side to its center line or bed of the road. In each set of deflecting fences or walls the one, *f''*, farthest from the mouth of the cut is prolonged to form a guide, *g*, which is 85 made to extend a short distance into the cut, and run parallel with the axis thereof. These deflecting fences or walls may be made of any material, but should present a smooth, unbroken surface to the wind, and the whole 90 may be roofed in for both better security against storms and greatly-increased effect.

To illustrate the operation of our device, let us suppose the wind to be blowing in the direction indicated by the arrow *d*. That portion 95 blowing over the cut will tend to form a partial vacuum on the line *c*, and to cause a drift within the cut. The wind blowing between the spread-

ing ends of the deflecting fences or walls $f f'$ 5
 f' , or on the side of the cut toward which the
wind is blowing, will be converged toward the
point X, and be guided by the guide fence or
wall g into the cut b, and will effectually pre-
vent the formation of a vacuum on the line c
by supplying air along said line as fast as it
is drawn out by the wind blowing as shown
by the arrow d. The constant current from
the deflecting-fences will not only prevent the
formation of a vacuum on the line c, but will
cause an upward current from the cut, which
will prevent the falling of any ice or snow
from above, and thus accomplish the end
sought.

We do not wish to limit ourselves to the use
of deflecting fences or walls at the ends of the
cut, for it is obvious that they may be made
effective at points along the line of the cut,
and similar devices may be used to prevent
the formation of drifts in traveled mountain
passes, and in sundry localities in cities and
towns.

What we claim as our invention is—

1. A snow drift or blockade preventer con- 25
sisting of one or more fences or walls, ar-
ranged substantially as described and shown,
and adapted to deflect currents of air in a lon-
gitudinal direction into a railroad-cut, in trav-
eled mountain passes, or behind obstructions, 30
substantially as and for the purpose set forth.

2. The combination, at a railroad-cut, and
to prevent a snow drift or blockade from form- 35
ing therein, of two or more deflecting fences
or walls converging toward a point conven-
iently near the cut, and a guide-fence to lead
the deflected current of air into the cut, sub-
stantially as for the purposes set forth.

Signed at Laurel, in the county of Prince
George and State of Maryland, this 14th day 40
of March, A. D. 1885.
